UNITED STATES PATENT OFFICE.

BY WILLIAM W. MCKELVEY, OF YOUNGSTOWN, OHIO, ASSIGNOR TO THE WILLIAM B.
POLLOCK COMPANY, OF YOUNGSTOWN, OHIO, A CORPORATION OF OHIO.

LADLE-CAR

5.1.021.543.

Specification of Letters Patent. Patented Mar. 26, 1912.

Application filed April 22, 1911. Serial No. 622,838.

- To all whom it may concern:

Be it known that I, WILLIAM W. MCKEL-
VER, of Youngstown, Mahoning county,
Ohio, have invented a new and useful Im-
provement in Ladle-Cars, of which the fol-
lowing is a full, clear, and exact description,
reference being had to the accompanying
drawings, forming part of this specification,
in which—

10 Figure 1 is an end view of a ladle car embodying my invention; and Fig. 2 is a similar view, largely diagrammatic, illustrating the dumping movement of the ladle.

My invention has relation to ladle or hot metal cars of the type which are emptied by pouring from the spout located at or near the top of the ladle. In cars of this character as ordinarily constructed heretofore, when the ladle is tipped in the frame of the car there is a considerable drop to the spout in the pouring operation. In order to bring the final position of the spout in the proper relation to the receptacle poured into, it has been necessary either to allow considerable fall to the metal during the first part of the pouring, or to lift the ladle from the car by means of an overhead crane and place it in a tilting cradle so arranged as to give a shorter fall to the metal; or else, to provide a movable trough which moves with the spout on the ladle. The first of these expedients results in considerable loss, due to splashing of the metal, and the other methods mentioned are subject to considerable inconvenience and expense in the handling operations.

The object of my invention is to provide a ladle arranged to tip to discharge its contents in the novel manner hereinafter described, and whereby the objections above noted are overcome.

In the accompanying drawings, the numeral 2 designates the frame and supporting wheels of a ladle car, which may be in general form as shown in Fig. 2.

45 eral of any usual or approved construction.
3 is the ladle having at each end and below its horizontal center and at opposite sides of its vertical center, the two trunnions 4 and 5, these trunnions being carried in open 50 trunnion seats or recesses 6 in the end frames 2^a of the car. The trunnions 4 and 5 are preferably parts of trunnion castings 7, secured to the car. 8 and 9 designate two other trunnions arranged near the top of

the ladle and at opposite sides thereof; 10 designates the lifting lugs on the ladle to which the tipping means are attached; and 11 is a stand located at one side of the car in position to receive the trunnion 9.

The receptacle for receiving the metal 60 poured from the ladle is indicated at 12. The stand 11 is formed with an open top rest or bearing recess 13 for the trunnion 9.

In the operation of pouring into the receptacle 12, the ladle is first tilted upon the trunnions 5, into a position to bring the trunnion 9 into the bearing 13 of the stand 11, as shown in Fig. 2. Any further lifting upon the lifting lug 10 causes the trunnion 5 to lift entirely out of its bearing 6, and the further tilting movement is wholly upon the trunnion 9, until the final position such as indicated in Fig. 2, is reached. 65 70

The foregoing describes the operation in pouring into a receptacle located at the right-hand side of the car looking at the drawing. In pouring to the left, a suitable stand similar to the stand 11, will be provided at the left-hand side of the car, and the tilting operations will take place on the trunnions 4 and 8. 75 80

By the provision of means whereby the ladle is tipped partly upon the bearing or bearings supported by the car and partly upon a bearing or bearings supported independently of the car, the drop in the spout during the pouring operation is materially lessened.

It will, of course, be obvious that the ladle may be provided with any desired number of points of support, either upon the car or upon the stand 11, and that various other changes may be made in the details of construction and arrangement of the parts without departing from the spirit and scope of my invention as defined in the appended claims. 95

What I claim is:—

1. A ladle car having a ladle provided with a tiltable support on the car at one level, means on the ladle at a higher level to tiltably engage another support, and other means adapted to engage a tipping device independent of the ladle and car; substantially as described. 105

2. A ladle having a lower support, a car upon which said support has a normal bearing, another support near the top of the car,

and a bearing for the last named support carried independently of the car; substantially as described.

3. A dumping car having a ladle provided with two sets of supports, and bearings therefor, whereby its dumping or tipping movement is partly upon a bearing supported by the car and partly on a bearing supported independently of the car; substantially as described.

4. A dumping car provided with a plurality of open bearings, a ladle having a plurality of supports normally engaging said bearings, and other supports at a higher level, together with means independent of the car to engage the last named supports and form a bearing therefor; substantially as described.

5. A dumping ladle having supports at different distances from the top thereof, a car having a bearing for the lower support, and a supporting member independent of the car and adapted to provide a bearing

for the upper support; substantially as described.

6. A ladle car having a tilting ladle; said ladle having a plurality of bearings, together with a fixed bearing located adjacent to the track on which the car is arranged to move substantially as described.

7. A dumping car having a ladle provided with two sets of supporting members, both located to one side of the vertical center of the car, and at different distances therefrom, and at different vertical heights, the car having bearings for one set of said members, and a support for the other set of said members which is mounted independently of the car; substantially as described.

In testimony whereof, I have hereunto set my hand.

W. W. McKELVEY.
